Primary Examiner — Richard E Chilcot*(74) Attorney, Agent, or Firm* — Lucian Wayne Beavers; Patterson Intellectual Property Law, PC(57) **CLAIM**

The ornamental design for milling tool, as shown and described.

DESCRIPTION

Fig. 1.1 bottom view of the milling tool.

Fig. 1.2 is right side elevation view of the milling tool of Fig. 1.1.

Fig. 1.3 is a front elevation view of the milling tool of Fig. 1.1.

Fig. 1.4 is a left side view of the milling tool of Fig. 1.1.

Fig. 1.5 is a rear elevation view of the milling tool of Fig. 1.1.

Fig. 1.6 is top view of the milling tool of Fig. 1.1.

Fig. 1.7 is left front perspective view of the milling tool of Fig. 1.1.

1 Claim, 7 Drawing Sheets(56)
